UNITED STATES PATENT OFFICE

VALRIE E. McMAHAN, OF WASHINGTON, DISTRICT OF COLUMBIA

DESIGN FOR A DOLL

Application filed March 16, 1933. Serial No. 47,473. Term of patent 14 years.

To all whom it may concern:

Be it known that I, VALRIE E. McMAHAN, a citizen of the United States, residing in Washington, in the District of Columbia, have invented a new, original, and ornamental Design for Dolls, of which the following is a specification, reference being had to the accompanying drawing.

In the accompanying drawing:

I claim:

The ornamental design for a doll, as shown. In testimony whereof, I hereunto affix my signature.

VALRIE E. McMAHAN.
